CLAIM

The ornamental design for a housing with a heat sink for an electrical connector, as shown and described.

DESCRIPTION

FIG. 1 is a front perspective view of a housing with a heat sink for an electrical connector showing our new design; FIG. 2 is a rear perspective view in which the environment has been removed for clarity of illustration; FIG. 3 is a front side elevational view thereof; FIG. 4 is a rear side elevational view thereof; FIG. 5 is a right side elevational view thereof; FIG. 6 is a left side elevational view thereof; FIG. 7 is a top plan view thereof; and, FIG. 8 is a bottom view thereof.

The broken lines portion of the figure drawings is included to show portions of the article that form no part of the claimed design.
